UNITED STATES PATENT OFFICE.

JOSEPH M. REDINGER, OF JOHNSTON, RHODE ISLAND.

IGNITION DEVICE.

Application filed July 18, 1927. Serial No. 206,503.

This invention relates to an ignition device of the pyrophoric type; and has for its object to provide a mounting for the pyrophoric material and a friction wheel which engages therewith which may be swung towards the wick to be lighted upon operation for ignition of the wick.

A further object of the invention is to provide a resilient mounting for the cover for the wick which may be lifted from the wick and swung to one side and expose the same for ignition purposes.

The invention further consists in the mounting of the wick cover supporting means and a resilient pyrophoric tube and friction wheel in parallel arrangement on the top of the fuel reservoir in such position that the device may be constructed to be conveniently carried about in the pocket of the user.

With these and other objects in view, the invention consists of certain novel features of construction, as will be more fully described, and particularly pointed out in the appended claims.

In the accompanying drawings:

Figure 1 is a side elevation partly broken away to show in section the resilient pyrophoric tube and its mounting on the fuel reservoir and also the filling plug for the reservoir.

Fig. 2 is a section on line 2—2 of Figure 1.

Figure 3 is a top plan view of the ignition mechanism mounted upon a fuel reservoir.

Figure 4 is a section on line 4—4 of Figure 3 with the bottom portion of the fuel reservoir broken away.

Figure 5 is a side elevation partly in section illustrating the ignition device as mounted upon a standard for desk or table use.

Figure 6 is a detail sectional view of the bifurcated end of the pyrophoric tube.

It is found in practice desirable to provide an ignition device which may be constructed to be used as a pocket lighter for cigars or cigarettes, or which may be mounted upon a standard for desk use or the like, which will be simple and positive in its operation and inexpensive to manufacture and in order to provide such a device, I have mounted on the top of the fuel reservoir having a wick extending therefrom a covering for the wick, which is supported by a flexible helically coiled wire or other material which may be lifted from a crotched post to hold the same in position and swung upon

a hinge mounting to one side to expose the wick and I have provided a similar helically coiled resilient flexible section in the arm which supports the pyrophoric material and have bifurcated the end to receive an abrasive wheel which may be rotated and at the same time swung towards the wick to throw a shower of sparks from the pyrophoric material directly upon the wick to ignite the same, and the following is a detailed description of the present embodiment of this invention and showing one means by which these advantageous results may be accomplished:

With reference to the drawings, 10 designates the fuel reservoir which is of a size and shape to be conveniently placed in the pocket of the user. This reservoir is filled with some absorbent material 11 and is provided with a filling opening 12 closed by a suitable plug 13 having threaded engagement therewith. The fuel reservoir may be of any suitable shape but is here illustrated as having beveled corners to enhance the appearance of the same. Extending upwardly from the reservoir there is a wick 14 to absorb and carry the fuel from the reservoir to its end for ignition purposes.

This wick is mounted in suitable guide and supporting sleeve 15 and extends beyond the same as at 17 a suitable distance. A wick cover 18 has an inclined lower edge 19 which closely fits the tapered shouldered edge 20 of the sleeve 15 to seal the wick and prevent evaporation of the fuel and also to snuff out the lighted wick when desired. This cover is mounted on an arm 21 which is hinged to a post 22 fixed to the top of the reservoir 10 by means of a pivot screw 23 extending through the bearing portion 24 of the arm. Between the bearing portion 24 and the cover there is a section 25 of helically coiled wire which has sufficient inherent resiliency tending to maintain the arm in a straight or rectilinear position and the cover tightly seated upon the shoulder 20 of the sleeve 15. A post 26 having a crotched end 27 engages the sides of this arm to prevent its swinging on the hinge pivot 23. However, when it is desired to remove the cover from the wick for ignition purposes a handle 28 is engaged and the cover lifted by flexing the section 25 of the arm 21, as illustrated in dotted lines in Figure 4, and swung on the pivot pin 23 to the position illustrated in Figure 3.

Located in normally parallel arrangement

with the wick cover mounting arm there is provided a helically coiled tube 29 having a support 30 mounted on the fuel reservoir with a sleeve 31 at one end which is bifurcated providing two finger portions 32 and 33 between which a friction wheel 34 is mounted on a shaft 35 which may be rotated by a thumb wheel 36 also fixed upon the shaft 35. Pyrophoric material 37 is positioned within the flexible tube and pressed into engagement by a spring 38 which may be adjusted by a finger wheel 40 of an abutment screw 39 threadedly mounted in the support 30 for this purpose.

15 When it is desired to ignite the wick the cover is removed as previously described and the thumb 41 in the position as illustrated in Figure 4 is moved in the direction of the arrow 42 to rotate the friction wheel to cause the shower of sparks to be thrown against the wick 14 to ignite the same. A pressure of the thumb on the thumb wheel 36 which will cause sufficient friction to rotate the wheel will also cause the flexible resilient tube 25 to swing towards the wick so as to more positively insure the shower of sparks thrown from the pyrophoric material coming in direct contact with the wick and insure its ignition.

30 In some cases, I may form this device as a stand for a desk in the general shape of a candlestick, as illustrated in Figure 5 having a base 43 with an imitation candle portion 44 formed as a fuel reservoir which may be filled through an opening 45 closed by a threaded plug 46 attached to the base portion of the device, the ignition for the wick being mounted upon the top of the fuel reservoir 44 in the same manner and to operate in the same way as upon the top of the fuel reservoir heretofore described in Figures 1 to 4.

45 It will be apparent that I have provided a means by which the sparks from the pyrophoric material may be brought closer to the wick tube at the time of ignition and yet the igniting mechanism may return by its own resiliency to its normal position away from the wick tube after operation of the same so that the heat of the flame will not affect the temper of the hardened wheel, this result being embodied in a simple and practical construction which may be inexpensively produced.

50 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

55 1. In an ignition device, a fuel reservoir, a wick extending therefrom, an elastic arm mounted on said reservoir, pyrophoric material and a spark wheel carried by said arm,

said arm being adapted to be swung towards said wick and to return to normal position away from said wick.

2. In an ignition device, a fuel reservoir, a wick extending therefrom, an elastic support, a pyrophoric element and a spark wheel carried by said support, said wheel being in contact with said element and normally widely spaced from said wick, said support and its wheel upon being actuated moving by 75 pressure of the manual actuation into proximity to said wick to ignite the same and upon being released to automatically return to its normal widely spaced position.

3. In an ignition device, a fuel reservoir, 80 a wick extending therefrom, an elastic tube mounted on said reservoir for resilient movement of one end towards said wick, pyrophoric material in said tube, and a spark wheel carried by said tube at said movable 85 end for engagement with said pyrophoric material, the said engagement being at a point in proximity to said wick.

4. In an ignition device, a fuel reservoir, a wick extending therefrom, a tube having a 90 resilient flexible section to permit it to be swung towards said wick, a friction wheel mounted in one end of said tube, pyrophoric material in said tube in engagement with said wheel and a thumb wheel for rotating said friction wheel to throw a shower of sparks onto said wick.

5. In an ignition device, a fuel reservoir, a wick extending therefrom, a tube having 100 a section formed of helically wound material to permit flexing towards said wick, said tube having a bifurcated end, a friction wheel located between said bifurcations of said end, a shaft rotatably supporting said friction wheel, a thumb wheel on said shaft for rotating the friction wheel, the pressure on the thumb wheel necessary for operating the friction wheel also serving to at the same time swing the tube towards the wick.

6. In an ignition device, a fuel reservoir, a 110 wick extending therefrom, pyrophoric means for igniting the wick, a cover for said wick, and a flexible support for said cover permitting the same to be swung at right angles to the plane of the wick to one side to expose the 115 wick.

7. In an ignition device, a fuel reservoir, a 120 wick extending therefrom, pyrophoric means for igniting the wick, a cover for said wick, means for hingedly supporting said cover to swing in a plane at right angles to the wick, and means cooperating with the hinging means for holding the cover in closed position.

8. In an ignition device, a fuel reservoir, a 125 wick extending therefrom, pyrophoric means for igniting the wick, a cover for said wick, means for hingedly supporting said cover including a resilient flexible section, a retaining post on the reservoir for holding said sup-

porting means and cover in wick-covering position, said flexible section permitting the supporting means and cover to be lifted from covering position and swung to one side to 5 expose the wick.

9. In an ignition device, a fuel reservoir, a wick extending therefrom, pyrophoric means for igniting the wick, a cover for said wick, means for hingedly supporting said 10 cover including a section of helically coiled material having an inherent resiliency to hold the same in axial alignment, a post on the reservoir having a crotch end for supporting and holding the cover in wick-cover- 15 ing position, said coiled section permitting the cover supporting means to be lifted from said crotch and swung on its hinge to remove the cover and expose the wick.

10. In an ignition device, a fuel reservoir, 20 a wick extending therefrom, a pair of parallel flexible tubes on said reservoir, a cover for said wick carried by one of said tubes, pyro-

phoric material and a sparking wheel carried by the other of said tubes and contacting at a point adjacent said wick, said cover being 25 removed from the wick by flexing the tube carrier, and said spark wheel and pyrophoric material being moved toward the wick by flexing the other tube.

11. In an ignition device, a fuel reservoir, 30 a wick extending therefrom, a pair of parallel flexible resilient tubes each tending to maintain axial alignment, a cover for the wick carried by one of said tubes, the cover carrying tube permitting flexing for lifting 35 the cover therefrom, pyrophoric material in the other tube and a spark wheel carried thereby for contacting therewith at a point adjacent the wick, and a thumb wheel on the pyrophoric tube for rotating the spark wheel 40 while the same is swung by pressure of the thumb towards the wick.

In testimony whereof I affix my signature.
JOSEPH M. REDINGER.
